UNITED STATES PATENT OFFICE.

JOHAN VIKTOR BLOMQUIST, OF DJURSHOLMS ÖSBY, SWEDEN.

STEAM PLANT.

1,301,806.

Specification of Letters Patent. Patented Apr. 29, 1919.

Application filed March 27, 1918. Serial No. 225,008.

To all whom it may concern:

Be it known that I, JOHAN VIKTOR BLOMQUIST, a citizen of Sweden, residing at Djursholms Öby, Sweden, have invented 5 certain new and useful Improvements in Steam Plants, of which the following is a specification.

It is well known that the pressure used in steam plants nowadays is increased as much 10 as possible. But hitherto it has not been possible to increase the pressure in existing steam plants beyond the maximum pressure for which the boilers are constructed. The 15 object of the present invention is to provide means for increasing the steam pressure in existing plants. With this object in view, the invention consists in certain novel features and combinations of parts, as will be more fully hereinafter described, reference 20 being had to the accompanying drawing.

1 represents a boiler constructd for a pressure as hitherto ordinarily used from which the steam passes through the pipe 8 for instance to the steam turbine 9 performing 25 useful work in the same. Revoluble steam generator elements 4 are mounted in the furnace under the boiler, the water preheated in the boiler 1 being fed through the pipe 2 by the pump 3 into said revoluble vessels so 30 as to evaporate in these at a considerably higher pressure, for instance 50 atmospheres, than the one prevailing in the boiler 1. After eventual superheating within the revoluble vessels the steam is carried from the 35

back pressure turbine 6 wherein the high-pressure steam expands to the pressure prevailing in the boiler 1, whereafter it passes through the exhaust steam pipe 7 into the 40 steam supply pipe 8 in order to work in the turbine 9 together with the steam from the boiler 1. As the revoluble vessels 4 are arranged within the fire box of the furnace and between the fire and boiler, it is obvious 45 that the superheating of the steam occurs simultaneously with the heating of the water in the boiler.

Having thus described my invention I claim and desire to secure by Letters Pat- 50 ent:—

In a steam plant of the character de- 55 scribed, a low pressure boiler having a fire box, a plurality of revoluble steam generator vessels arranged within the fire box beneath the boiler and between the same and the grate or fire, a pipe connected with the boiler to supply preheated water to the revoluble vessels, a steam pipe leading to the boiler, a low pressure engine connected with 60 the steam pipe, a high pressure engine having its exhaust connected with the steam pipe, and a second steam pipe connected with the revoluble vessels and the intake of the high pressure engine. 65

In testimony whereof, I have signed my name to this specification in the presence of two subscribing witnesses.

JOHAN VIKTOR BLOMQUIST.

Witnesses:

HANS HYLANDER,
OTTO BURMEISTER.
